UNITED STATES PATENT OFFICE

151,859

DESIGN FOR A CABINET FOR RADIO- PHONOGRAPH COMBINATION

Wallace Schier, Forest Hills, and David L. Doggett, Mount Kisco, N. Y., assignors to Federal Telephone and Radio Corporation, New York, N. Y., a corporation of Delaware

Application January 11, 1947, Serial No. 136,077

Term of patent 3½ years

(Cl. D56—4)

To all whom it may concern:

Be it known that we, Wallace Schier and David L. Doggett, citizens of the United States, residing at 150 Greenway Terrace, Forest Hills, Long Island, New York, and Millwood Road, Mount Kisco, New York, respectively, have invented a new, original, and ornamental Design for a Cabinet for Radio-Phonograph Combination, of which the following is a specification, reference being had to the accompanying drawing, forming part thereof.

Figure 1 is a perspective view of the cabinet;

Figure 2 is a plan view of the cabinet with the radio and phonograph units shown in open position, the cabinet being rotated about its vertical axis approximately 90 degrees from the position shown in Figure 1; and

Figure 3 is a front elevational view of the cabinet as shown in Figure 2.

The characteristic features of our design reside in the portions shown by means of solid lines.

We claim:

The ornamental design for a cabinet for radio-phonograph combination, substantially as shown and described.

WALLACE SCHIER.
DAVID L. DOGGETT.
